UNITED STATES PATENT OFFICE.

LINDLEY D. HUEBELL, OF HARTFORD, CONNECTICUT.

FIREARM.

1,352,267.

Specification of Letters Patent.

Patented Sept. 7, 1920.

Application filed April 7, 1920. Serial No. 371,899.

To all whom it may concern:

Be it known that I, LINDLEY D. HUEBELL, a citizen of the United States, and resident of Hartford, county of Hartford, State of Connecticut, have invented certain new and useful Improvements in Firearms, of which the following is a specification.

This invention relates generally to automatic firearms and it more specially relates 10 to a firearm of that class which comprises a frame, provided with a cartridge magazine, a barrel supported by the frame, and a breech-slide mounted to reciprocate upon the frame for opening and closing the firing 15 chamber of the barrel. When a cartridge is fired, the breech-slide recoils to the open rear position, thereby extracting the empty cartridge shell from the barrel and ejecting the shell from the firearm and receiving another cartridge from the magazine for insertion into the chamber of the barrel during 20 the ensuing forward closing movement of the breech-slide, under the reaction of a spring in which energy was stored during 25 the opening movement.

In accordance with the present invention, I provide a single latch which serves as a side safety to lock the hammer and also serves to lock the slide in retracted position, 30 this being of advantage in that the construction is simplified, the number of parts being reduced to a minimum and, therefore, economy in manufacture and ease in manipulation is obtained. Also, the latch may 35 be operated to release the slide or the hammer without shifting the hand holding the firearm or otherwise interfering with the aiming of the firearm.

In the accompanying drawing, wherein 0 the preferred embodiment of the invention is illustrated,

Figure 1 is a side view of a pistol to which my invention is applied, the latch being shown in the position in which the hammer is locked.

Fig. 2 is a similar view showing the latch locking the slide in retracted position.

Fig. 3 is an inside view of the latch, and

Fig. 4 is a side view, partly in section, of the magazine.

In the drawings, I have shown, by way of illustration only, a pistol of a well known make but it is to be understood that the present invention has general application to firearms of this general type. As firearms of this sort are old and well known, only

so much of the construction thereof is illustrated and described as is deemed necessary to make the application of the invention clear. The firearm is shown as having a 60 frame *a*; a slide *b* slidably mounted thereon; a hammer *c* adapted to be actuated by the trigger *d* acting through the sear *e*, shown in dotted lines in Fig. 1; a safety grip *f* which must be gripped to permit pulling of 65 the trigger, and a magazine *g* having a spring actuated plunger *h*.

The present invention relates more particularly to the locking latch designated by the numeral 10 and now to be described. 70 This latch is, so far as it serves to lock the hammer in cocked position, similar in arrangement and construction to the usual side safety. The latch, as is usual, may have a pin 11 whereby the latch is pivoted to the 75 frame of the pistol. The manner in which this side safety is associated with the hammer to lock the same may be varied, but by way of illustration I have shown an old arrangement wherein the latch carries an 80 inwardly extending lug 12 which, when the latch is in the locking position illustrated in Fig. 1, is in the path of the lower end of the sear *e* preventing actuation of the latter. When the latch is swung down, the 85 notch 12^a in the lug 12 is brought opposite the lower end of the sear *e* so that the latter may be actuated by the trigger to release the hammer. In accordance with the present invention, interengaging means are provided on the latch 10 and slide *b* for locking the latter in retracted position, and this means is automatically rendered effective by the follower of the magazine after the last cartridge has been fired. By way of example, the latch is shown as having on its upper edge a projection 13 and in the lower edge of the slide is a notch 14 so located that when the slide is in its retracted position, as illustrated in Fig. 2, the projection may 90 engage in the notch to lock the slide. The latch 10 may be raised by the follower into locking engagement with the slide in any suitable manner, but for illustrative purposes, the latch is shown as having adjacent 95 its free end an inwardly projecting stud 15 extending through an opening 16 in the side of the frame and into the path of travel of a pin 17 extending from one side of the follower *h* and operating in a slot 18 in the 100 side wall of the magazine *g*. As shown in Fig. 2, after the last cartridge has been fed

from the magazine into the barrel, the pin 17 engages the stud 15 whereby the latch is urged into raised position so that after the last cartridge has been fired the projection 5 13 will engage in the notch 14 and lock the slide in its retracted position. Thus when a filled magazine is substituted for the empty one, the slide will be in position to receive the first cartridge. The latch may 10 then be lowered by the thumb of the operator to release the slide without shifting the hand holding the pistol.

The letter *i* designates the usual spring 15 pressed plunger for preventing accidental displacement of the latch.

I claim as my invention:

1. In a firearm of the character described, a frame, a breech-slide mounted for reciprocation thereon, a magazine including a follower, 20 a single means for locking the hammer in cocked position and locking the slide in retracted position and interengaging means between said follower and locking means whereby the latter is actuated by said follower.
2. In a firearm of the character described, a frame, a breech-slide mounted for reciprocation thereon, a magazine including a follower, 25 a single means having a portion for

locking the hammer in cocked position and another portion for interengagement with the slide to lock the same in retracted position and interengaging means between said follower and single means whereby the latter is moved into locking relation to said slide when the last cartridge has been fired. 35

3. In a firearm of the character described, a slide slidable thereon, a hammer, a magazine having a follower, a single latch having means for locking said hammer and means 40 for locking said slide in retracted position, and interengaging means between latch and follower whereby said latch is moved into locking relation to said slide after the last cartridge has been fired. 45

4. In a firearm of the character described, a frame, a slide thereon having a notch, a hammer, a magazine including a follower, a side safety for locking the hammer in cocked position and having a projection 50 adapted to engage in the notch of said slide to lock the latter in retracted position, and interengaging means between said follower and side safety whereby the latter is moved into locking relation to said slide when the 55 last cartridge has been fired.

LINDLEY D. HUBBELL.
